UNITED STATES PATENT OFFICE

JOHN L. VAUGHN, OF CICERO, ILLINOIS, ASSIGNOR TO O. D. JENNINGS & COMPANY, OF CHICAGO, ILLINOIS, A CORPORATION OF ILLINOIS

COIN OPERATED TIME CONTROLLED SWITCH MECHANISM

Application filed November 28, 1930, Serial No. 498,577.

This invention relates to coin operated time controlled switches of the type employed to control an electric circuit.

It is frequently desirable to maintain an uninterrupted flow of current with such a device but in prior devices of this nature the switch was opened for a brief period occasioned by the discharge of one coin and the replacement of it by another. This interruption occurred even when the coin chute was full of coins.

It is the purpose of this invention to provide a switch of this character which will remain closed and maintain an uninterrupted flow of current as long as there are coins in the coin chute and in which the coin is the actuating medium but does not constitute part of the circuit. It is a further object to provide a switch of the above type in which the circuit will be unbroken during the continuous passage of coins through the chute.

Other features and resultant advantages of this invention will be apparent from the following description given in connection with the drawing in which:

Fig. 1 is a front elevation of a coin operated time controlled switch constructed in accordance with this invention.

Fig. 2 is an end elevation with the coin chute removed, and

Fig. 3 is a detailed end elevation of the coin chute and switch mechanism.

In the illustrated embodiment of this invention the device is one that is suitable for controlling the current supply to a radio receiver or equivalent apparatus. It is apparent that any other apparatus may be controlled accordingly. The current from any suitable source is brought in through two wires 1 and 2 and goes out through a pair of conductors 3 and 4. Conductor 1 connects to a common terminal strip 6 from which one lead 7 is taken to the electric motor 8. One conductor 3 from the radio receiver or equivalent apparatus is also connected to the common terminal block 6.

The other conductor 2 from the source of current is attached to a terminal 9 which supports one contact 11 of an electric switch. The other contact 12 is carried by a resilient

switch arm 13 which is connected by a wire 14 to a terminal strip 16. The other outgoing lead 4 is connected to terminal strip 16 as is the lead to motor 8. It follows from the above wiring that when switch contacts 11 and 12 are closed the motor 8 as well as the apparatus connected to wires 3 and 4 will receive current from wires 1 and 2.

The coin controlled time operating mechanism for actuating switch contacts 11 and 12 will now be described. In general the motor 8 and its associated train of gears 18 are mounted between a pair of spaced end plates 19 the latter being supported upon a back plate 21 and being preferably formed of some insulating material.

The coin chute 22 is also supported by one of the end plates 19. The chute 22 is provided with the usual trips 23 and 24 to prevent the passage of improper coins therethrough. The lower portion of the chute is provided with an arcuate cutaway portion 26 along one edge thereof to expose a portion of the periphery of the coins as they pass through the chute. A spring pressed lever 27 entering a slot in the chute prevents discharge of the coins from the slot unless positively removed therefrom.

The switch arm 13 is secured to the upper end of a switch lever 28 pivoted intermediate its ends at 29 upon an insulated bushing 31. The lower end of switch lever 28 terminates in an arcuate contact portion 32 which, due to the action of a spring 33, will normally lie in the arcuate cutaway portion 26 the curvature of the portion 32 being substantially the same as the cutaway edge of chute 22. The end 32 will thereby be engaged by the peripheral edge of the coins as they drop through the chute. The action of coins passing through the chute is to move the lower end 32 of lever 28 to the left about pivot 29 to close contacts 11 and 12 the two positions being clearly shown in Figs. 1 and 3.

In order to provide a time control for the contacts 11 and 12, a motor 8 is provided which drives the train of gears 18 which in turn drive a final shaft 34. Shaft 34 carries an arm 36, the outer end of which is pro-

vided with a latterly projecting roller 37. The length of arm 36 and roller 37 is designed to enter between the cutaway edge of chute 26 and the arcuate end 32 of lever 28 to engage the coins as well as the arcuate member 32. The arm thus performs a dual function, that is, roller 37 engages the periphery of the coins to eject the coins from the chute pushing the coins past lever 27 and engages arm 32 to hold switch contacts 11 and 12 closed during the ejection of the coin to permit the entry of a successive coin without permitting an opening movement of lever 28 to open contacts 11 and 12. Therefore, as long as there is an uninterrupted succession of coils in the chute, contacts 11 and 12 will be maintained closed and the motor and outgoing circuit will receive a continuous flow of current.

The operation of the foregoing apparatus is believed to be apparent from the above description but will be briefly summarized. Upon the insertion of a coin in chute 22, the coin will drop by gravity and engage end 32 of lever 28. The weight of the coin will move lever 28 to the left against the action of spring 33 and close contacts 11 and 12.

The closing of contacts 11 and 12 will establish a circuit from lines 1 and 2 to the motor 8 and also to the outgoing lines 3 and 4. The establishment of the circuit to motor 8 will cause a rotation of arm 36 in a clockwise direction. Rotation of arm 36 in due time will carry roller 37 between the end 32 and the arcuate edge of cutaway portion 26 where the roller 37 will engage the lowermost coin in the chute and eject the same from the chute by pushing the coin beyond lever 27. At the same time roller 37 by its engagement with end 32 of lever 28 will maintain contacts 11 and 12 closed during the ejection of the lowermost coin and will permit the entry of a succeeding coin without permitting opening of contacts 11 and 12. It is understood of course that the time interval during which contacts 11 and 12 are closed is determined by gear reduction of gear train 18.

It is obvious that the term coin is used to include any coin check, token or similar article and that many changes may be made in the details of construction without departing from the spirit and scope of this invention as defined in the appended claims.

I claim:

1. In a coin operated time controlled switch mechanism, a coin chute, a switch operable by a coin in said chute, means for retaining said coin in operative position in said chute, means for ejecting the coin from said chute at the expiration of a predetermined time period and means for maintaining said switch against movement for a predetermined time period after said coin has been ejected.

2. In a coin operated time controlled switch mechanism, a coin chute, a switch operable by

a coin in said chute, means for retaining said coin in operative position in said chute to hold said switch closed, a motor for controlling the period during which said switch is closed and means for engaging a coin to discharge the same and to simultaneously maintain said switch closed while a coin is being ejected from its operative position.

3. In a coin operated time controlled switch mechanism, a coin chute for conducting coins through said mechanism, a switch contact, a switch lever, a second switch contact movable by said lever, said lever extending into proximity to said coin chute and adapted to be engaged by a coin as it passes down said chute, means for retaining said coin in operative position in said chute to hold said switch closed, a motor for controlling the period for which said switch contacts are closed and a member arranged to engage said switch lever to maintain said switch contacts closed during the ejection of a coin from said chute.

4. In a coin operated time controlled switch mechanism, a coin chute for conducting coins through said mechanism, a switch contact, a switch lever, a second switch contact movable by said lever, said lever extending into proximity to said coin chute and adapted to be engaged by a coin as it passes down said chute, means for retaining said coin in operative position in said chute to hold said switch closed, a motor for controlling the period for which said switch contacts are closed, and a member adapted to eject a coin from said chute and to engage said lever while ejecting said coin to maintain said switch contacts closed during the ejection of said coin.

5. In a coin operated time controlled switch mechanism, a coin chute for conducting coins through said mechanism, a switch contact, a switch lever, a second switch contact movable by said lever, said lever extending into proximity to said coin chute and adapted to be engaged by a coin as it passes through said chute, means for retaining said coin in operative position in said chute, a motor for controlling the period for which said switch contacts are closed, an arm actuated by said motor and arranged to eject a coin from said chute and to engage said lever while ejecting said coin to maintain the switch contacts closed during the ejection of said coin.

6. In a coin operated time controlled switch mechanism, a coin chute for conducting coins through said mechanism, said chute having a cutaway portion, a switch contact, a pivoted switch lever, a second switch contact secured to said lever, said lever having a portion thereof extending into the cutaway portion of said chute whereby the lever may be engaged by a coin as it passes through said chute, means for retaining said coin in operative position in said chute to hold said switch closed and a motor for controlling the period during which said switch contacts are closed and having

- means associated therewith for ejecting said coin after a predetermined period of time.
7. In a coin operated time controlled switch mechanism, a coin chute for conducting coins through said mechanism, said chute having a cutaway portion, a switch contact, a pivoted switch lever, a second switch contact secured to said lever, said lever having a portion thereof extending into the cutaway portion of said chute whereby the lever may be engaged by a coin as it passes down said chute, means for retaining said coin in operative position in said chute to hold said switch closed, a motor for controlling the period during which said switch contacts are closed and a rotary arm arranged to enter between said lever and said chute to eject the operating coin from said chute.
8. In a coin operated time controlled switch mechanism, a coin chute for conducting coins through said mechanism, said chute having a cutaway portion, a switch contact, a pivoted switch lever, a second switch contact secured to said lever, said lever having a portion thereof extending into the cutaway portion of said chute whereby the lever may be engaged by a coin as it passes through said chute, a motor for controlling the period during which said switch contacts are closed and a rotary arm arranged to enter between said lever and said chute to eject the operating coin from said chute and to engage said lever and maintain said switch contacts closed during the ejection of said coin.
9. In a coin operated time controlled switch mechanism, a coin chute for conducting coins through said mechanism, said chute having a cutaway portion, a switch contact, a pivoted switch lever, a second switch contact secured to said lever, said lever having a portion thereof extending into the cutaway portion of said chute whereby the lever may be engaged by a coin as it passes down said chute, a motor for controlling the period during which said switch contacts are closed and a rotary arm actuated by said motor and arranged to enter between said lever and said chute to eject the operating coin from said chute.
10. In a coin operated time controlled switch mechanism, a coin chute for conducting coins through said mechanism, said chute having a cutaway portion, a switch contact, a pivoted switch lever, a second switch contact secured to said lever, said lever having a portion thereof extending into the cutaway portion of said chute whereby the lever may be engaged by a coin as it passes through said chute, a motor for controlling the period during which said switch contacts are closed and a rotary arm actuated by said motor and arranged to enter between said lever and said chute to eject the operating coin from said chute and to engage said

lever and maintain said switch contacts closed during the ejection of said coin.

In witness of the foregoing I affix my signature.
